NEWTON C. SCHELLINGER, OF ELKHART, INDIANA, ASSIGNOR TO CHICAGO TELEPHONE SUPPLY COMPANY, OF ELKHART, INDIANA, A CORPORATION OF DELAWARE

TUBE MOUNTING

Application filed January 18, 1926. Serial No. 81,882.

The present invention relates to mountings for radio or thermionic tubes.

Manufacturers of radio tubes are now putting on the market tubes with longer contact studs and without any guide pins. This makes it possible to provide simple means for guiding the tube and more effective contact means for making contact with the studs.

10 I provide a novel form of tube mounting which is particularly adapted for the new types of tubes. In my mounting suitable openings are provided through which the studs of the tube are adapted to extend. Ad- 15 jacent each of these openings and on the under side of the mounting is a novel form of contact spring, each leg of which is so formed that it exerts an even 20 pressure against its co-operating stud in such a manner as to insure positive line contact on two sides of the studs. For this purpose I employ a generally U-shaped spring, each leg of which is so formed that it exerts an even 25 pressure along all points of contact against the studs. Furthermore, in my type of spring a wiping action is had between the stud and the spring along all points of contact when the tube is inserted into the mount- 30 ing. The result is that the contact surface is first cleaned of all dust and any oxide which may be formed thereon before final contact therewith is had. This automatic cleaning action is also insured by the twist- 35 ing action of the spring when the stud is brought to bear upon it.

Also, by employing a generally U-shaped spring, I am able to obtain a greater length of spring in less space than is usually required in tube mountings employing the ordinary flat type of spring. This feature is especially desirable for tube mountings or sockets which are to be used in radio receivers where it is oftentimes necessary to limit 45 the amount of space required for the tube mounting.

Although my spring is generally U-shaped, the legs thereof do not extend upward vertically as in a U, but out in a diagonal direction. This exposes the base portion of

the U so that free access may be had thereto for the purpose of fastening the spring to its mounting.

Also, the full length of each spring is effectively used in exerting pressure against 55 the tube stud which co-operates with it. This is accomplished by so shaping the legs that each portion thereof will tend to twist about its central longitudinal axis when the contact portions are forced into engagement 60 with the tube stud. In the ordinary type of springs now in use, there is only a bending action and not a combined bending and twisting action as in my spring. The twisting action is further brought about by making the legs convergent at their free ends. Hence the tube stud in forcing the legs apart 65 will cause a greater bending and twisting action with the result that firmer and better contact is obtained.

Still another feature of my invention is its relative simplicity. The springs which are employed are made of metal stamping, and as such are comparatively cheap and easy to manufacture.

In order to acquaint those skilled in the art with the manner of constructing my invention, I shall now describe an embodiment of the same in connection with the accompanying drawings.

In the drawings:—

Figure 1 is a front elevational view of one form of my invention, showing a tube mounted thereon;

Fig. 2 is a top plan view of the same;

Fig. 3 is a bottom view of the form shown in Fig. 1;

Fig. 4 is an enlarged sectional view taken on line 4—4 of Fig. 2;

Fig. 5 is a sectional view taken on line 90 5—5 of Fig. 4 before the stud of a tube has engaged with its co-operating spring;

Fig. 6 is also a view taken on line 5—5 of Fig. 4 after the stud is brought into engagement with its co-operating spring;

Fig. 7 is a top plan view of another embodiment of my invention;

Fig. 8 is a bottom view of same;

Fig. 9 is an enlarged sectional view taken on line 9—9 of Fig. 7;

Fig. 10 is an isometric view of a contact spring of my invention;

Fig. 11 is an isometric view which shows the legs of a simple form of box shaped 5 spring in solid lines, and the legs of my spring in dotted lines; and

Fig. 12 is an isometric view of another modification of my contact spring.

Similar numerals refer to similar parts 10 throughout the several views.

The tube mounting comprises a base portion 15 of insulating material 12 which is provided with a pair of openings 13 and also a pair of openings 14 having a larger diameter than the openings 13. These openings extend vertically through the base 12 and are 20 adapted to receive the studs of the tube 15. The tube studs are likewise paired off. The pair which is adapted to extend through the openings 14 is of a larger diameter than the pair which is to extend through the openings 13. By this arrangement the user can 25 not possibly get the stud through the wrong holes and into contact with the wrong contact springs, for the tube can not be inserted into its mounting unless the studs are aligned with their proper openings. Also, the upper end of each of the openings 13 and 14 is slightly counter-bored to seat the 30 flange on each of the studs which protrude through the base portion of the tube 15. The base member 12 is also provided with openings 16 through which suitable fastening screws may be inserted for securing the 35 base to a support member or other mounting means. The underside of the base 12 is provided with a depressed portion or recess 17 in which are mounted the contact springs 18 by means of suitable screw fastening 40 means 19. To prevent any sidewise or lateral movement of the springs, I provide suitable lugs or pins 32 which extend vertically 45 downward from the bottom side of the base member 12. These may be formed integral therewith in the die in which the base is formed, or they may be separate pins which have been placed in the forming die and 50 formed with the base. The screws 19 extend upwardly through the base 12 and are locked in place by means of the nuts 20. Each screw may also be provided with a suitable lug for soldering leads 21 thereto and a lock nut 22 for securing the lug firmly 55 against the nuts 20.

The gist of my invention consists in the novel provision of the contact springs 18. An isometric view of one of the contact springs 18 is shown in Fig. 10. It is formed 60 out of a single piece of spring metal and has a generally U-shape. The base portion 23 thereof is substantially flat and is rounded off at its outer end so as to furnish sufficient room for the opening 24 through which 65 the holding means for the spring is adapted

to extend. The inner edge of the base 23, however, is curved inwardly so as to fill out the corners between the base and the legs. It will also be noted that the base 23 has a generally triangular shape. A pair of legs 70 extend downwardly in a diagonal direction from the sides of this base and converge. These legs are integral with the base and are of substantially the same width throughout except at their free ends. At 75 their free ends both of the legs, both of which are designated in Fig. 10 by the numeral 25, are provided with an upwardly extending lug portion 26. These lugs are slightly bent to one side to permit the tube 80 studs to readily engage with them.

In Fig. 5 I have illustrated a tube stud 27 which is about to enter an opening in the base 12. The contact spring with which the stud is to engage has its lug member 26 directly below and in line with the opening. Now, as the stud 27 is forced through the opening and into engagement with the contact spring 18, it will force apart the leg 25 of the spring by giving it a slight twist, and 90 when the stud is in its final position it will be in firm contact with both legs of the spring. This is shown in Figs. 4 and 6.

The action and advantages of my spring 95 may be more fully brought out by comparing it with a box shaped spring shown in Fig. 11. In this figure the legs of the box spring are shown in solid lines and the legs of my spring in dotted lines. Now, when the tube stud is inserted between the legs of 100 the box spring, it will cause them to move out laterally by a bending action about a vertical axis which extends through a point at which the inner edge of the base and the upper edge of the legs meet, as shown by the 105 lines B—B and B'—B'. Hence, it is obvious that by this arrangement only a part of each leg is brought into action; the back portion, which is integral with the base, being held rigidly in place. However, if a 110 portion of each leg is cut away so that it takes the form shown by the dotted lines, the result will be quite different. Now, when the stud is forced between the legs, a combined bending and twisting action will 115 take place. The bending will again be about the axis B—B, but the twisting or turning will take place about the central longitudinal axis A—A. The twisting or turning is now permitted because the portion which 120 would hold the leg above the axis A—A from turning has been removed, and likewise that portion which would prevent the lower portion of the leg from turning has 125 also been removed. The result is that no resistance is offered to the legs either at their upper or lower sides, thereby making their full lengths effective for contact with a cooperating stud.

I find that when the stud is brought into 130

engagement with the contact spring that it tends to twist both legs of the spring out laterally. This seems to help materially in permitting the legs 25 to exert an even pressure against the tube stud. The result is that firm line contact is had on two sides of the stud for substantially the entire width of the leg members 25.

I may also employ my novel springs in various other ways. For example, I may mount them in the manner illustrated in Figs. 7, 8 and 9, in which a plate member 30 is employed. This member is adapted to serve as a mounting plate for a plurality of tubes and may be made of insulating material or may even be made of metal by properly insulating the various stud and screw openings. Otherwise, the essential novelty disclosed as to the embodiment shown in Fig. 1 is equally applicable to that shown in Figs. 7, 8 and 9.

In Fig. 12, I illustrate another form of contact spring. This spring comprises a generally triangular base portion 35, having an opening 36 for mounting purposes and a lug 37 integral therewith for making contact therewith. The lug 37 is adapted to extend through a suitable opening in the base on which the spring is mounted. The spring may be secured to its mounting base by means of a suitable rivet or screw which extends through the opening 36 therein. Projecting downwardly from each side of the base are a pair of generally U-shaped legs 38. These legs also converge at their free ends for making firmer contact with the stud which is adapted to cooperate with them.

It is also obvious that I may provide means on the base portion by which the spring may be secured to the mounting base without the use of the screw members and nuts shown. I may also provide a lug integral with the base 23 in the form shown in Fig. 10 which might extend upwardly or out laterally through the mounting base. Such a lug would serve a two-fold purpose. It would serve to hold the spring in place, and it would also serve as a means for making contact to the spring. Also, I may provide suitable seats or grooves for the base portion of the springs in the mounting member for preventing any possible lateral movement of the springs. However, I find that this is not necessary if the springs are firmly secured to the mounting member by the manufacturer.

I do not wish to be limited to the details shown or described.

60 I claim:—

1. A contact spring comprising a base portion and a pair of legs extending diagonally downward from said base portion.
2. A contact spring comprising a base portion and a pair of converging legs projecting

diagonally and downwardly from said base portion, said legs having a pair of upwardly extending lugs.

3. In combination, a mounting member having an opening for receiving a tube stud, a generally U-shaped spring member having a base portion and a pair of legs extending diagonally therefrom, and bolt means extending through said base portion for securing said spring to said mounting member.

4. In combination, a mounting member having a plurality of openings adapted to receive the studs of a thermionic tube, a plurality of spring members, each of said spring members comprising a base portion having an opening, and a pair of converging legs extending diagonally from the longitudinal sides of said base, the free ends of said legs being below and in substantial alignment with the openings in said mounting member, and bolt means extending through the openings in the base portions of said springs and through said mounting member for securing said springs thereto.

5. In combination, a thermionic tube mounting having an opening adapted to receive and constrain the movement of a stud of the tube, and spring means below the mounting adapted to make contact with the stud and comprising a base portion, a pair of converging legs extending diagonally downward from said base, the free ends of said legs being below and in substantial alignment with the opening in said mounting member and a pair of laterally extending ears formed integral with said free ends and being adapted to be initially engaged by the stud to flex the legs of said spring means, said diagonal slant of said legs permitting the free ends thereof to flex about both a vertical and a horizontal axis.

6. A contact spring comprising a base portion and a pair of legs depending therefrom at an acute angle in planes disposed at right angles to the plane of the base portion, the legs extending convergently outward beyond the base portion to permit the insertion of a stud therebetween, lugs on the outer ends of said legs disposed in the planes of the legs and having tips disposed at an angle thereto, the convergently extended portions of the legs being capable of spreading on reception of the stud contacting between the lugs, and being capable of warping to accommodate the lugs to the surfaces of the stud.

In witness whereof, I hereunto subscribe my name this 8th day of January, 1926.

NEWTON C. SCHELLINGER.
